US00D800410S

(12) **United States Design Patent** (10) Patent No.: **US D800,410 S**
(45) Date of Patent: **** Oct. 17, 2017**

(54) **MATERIAL HANDLING CART**

(71) Applicant: **AMIGO MOBILITY INTERNATIONAL, INC.**, Bridgeport, MI (US)

(72) Inventors: **Allen Louis Bussinger**, Bridgeport, MI (US); **Jeremiah Vincent Schultz**, Bridgeport, MI (US)

(73) Assignee: **AMIGO MOBILITY INTERNATIONAL, INC.**, Bridgeport, MI (US)

(**) Term: **15 Years**

(21) Appl. No.: **29/546,542**

(22) Filed: **Nov. 23, 2015**

(51) LOC (10) Cl. **12-05**

(52) U.S. Cl. **USPC D34/37; D34/34**

(58) **Field of Classification Search**

USPC D34/12, 17, 20, 21, 23, 26, 28, 18, 33, D34/34, 36, 37; 280/79.11, 79.3, 33.997, 280/47.19, 47.34, 47.35, 47.17; 180/65.51, 11, 19.3, 14.1, 65.1; 414/604, 414/814; 410/4

CPC B62B 3/10; B62B 3/00; B62B 3/04; B62B 5/0093; B62B 5/0438

See application file for complete search history.

(57) **CLAIM**

The ornamental design for a material handling cart, as shown and described.

DESCRIPTION

FIG. 1 is a top perspective view of a material handling cart showing our new design;

FIG. 2 is a bottom perspective view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a top perspective view thereof, in a storage condition; and,

FIG. 10 is a left side elevational view thereof, in a storage condition.

The broken lines in the drawings are included for the purpose of illustrating portions of the material handling cart and form no part of the claimed design.

1 Claim, 8 Drawing Sheets
